Primary Examiner — Kevin Rudzinski(74) *Attorney, Agent, or Firm* — Paul Y. Feng; The Eclipse Group, LLP(57) **CLAIM**

The ornamental design for an domed flush mount light fixture with clear, raised radial spokes on etched glass, as shown and described.

DESCRIPTION

FIG. 1 is a bottom view of a domed flush mount light fixture with clear, raised radial spokes on etched glass, showing the new design;

FIG. 2 is a top view of the domed flush mount light fixture with clear, raised radial spokes on etched glass from FIG. 1; FIG. 3 is a front elevational view thereof;

FIG. 4 is a rear elevational view thereof;

FIG. 5 is a left side elevational view thereof;

FIG. 6 is a right side elevational view thereof;

FIG. 7 is an upper perspective view thereof; and,

FIG. 8 is a bottom perspective view thereof.

The broken lines shown in the drawings illustrate environmental features and form no part of the claimed design.
